UNITED STATES PATENT OFFICE.

BENNETT HANSEN, OF MINNEAPOLIS, MINNESOTA.

DESIGN FOR AN ARCH.

Application filed May 25, 1923. Serial No. 6,287. Term of patent 7 years.

To all whom it may concern:

Be it known that I, BENNETT HANSEN, a citizen of the United States, residing at Minneapolis, in the county of Hennepin and

State of Minnesota, have invented a new Arch, of which the following is a specification, reference being had to the accompanying drawing, forming part thereof.

The figure is a perspective elevation of an arch for adjoining rooms, illustrating my new design.

I claim:

BENNETT HANSEN.
